UNITED STATES PATENT OFFICE.

THOMAS JEFERSON BLAGG, OF WAVERLY, NEBRASKA.

WEIGHT-MOTOR.

SPECIFICATION forming part of Letters Patent No. 349,872, dated September 28, 1886.

Application filed April 28, 1886. Serial No. 200,480. (No model.)

To all whom it may concern:

Be it known that I, THOMAS JEFERSON BLAGG, a citizen of the United States, residing at Waverly, in the county of Lancaster and State of Nebraska, have invented a new and useful Improvement in Weight-Motors, 5 of which the following is a specification.

My invention relates to an improvement in weight-motors; and it consists in the peculiar 10 construction and combination of devices that will be more fully set forth hereinafter, and particularly pointed out in the claims.

In the drawings, Figure 1 is a side elevation 15 of a weight-motor embodying my invention. Fig. 2 is an end elevation of the same. Fig. 3 is a horizontal section taken on the line xx of Fig. 1. Fig. 4 is a modification. Fig. 5 is a view of another modification, and Fig. 6 is a transverse section through drum F.

20 A represents a vertical supporting-frame, which is provided with a pair of parallel inclined track-bars, B, which are provided on their outer sides with projecting toothed racks C.

25 D represents a transverse shaft, which is journaled in the frame A. The said shaft carries a fixed spur-wheel, E, and a loose drum, F. One end of the drum F is provided with spur-teeth G.

30 H represents a transverse shaft, which is also journaled in suitable bearings with which the frame A is provided, and is parallel with the shaft D. The said shaft H is provided with a fixed pinion, I, which meshes with the 35 gear-teeth G of the drum, and to one end of the said shaft is attached a crank-handle, K. A ratchet-wheel, L, is secured rigidly to the shaft D, and the drum F is provided with a spring-actuated pawl or detent, M, which engages 40 with the said ratchet-wheel, and thereby causes the drum F to turn with the shaft D in the direction indicated by the arrow in Fig. 1. When the shaft D rotates in the reverse direction, the drum is free to remain stationary 45 thereon.

45 N represents a shaft, which is journaled above the shaft B, and is provided with a spurred pinion, O, which meshes with the wheel E, and has a crank-wheel, P, and a large 50 spur-wheel, R.

S represents a transverse shaft, which is

55 journaled above the shaft N, and is provided with a fixed spur-pinion, T, that meshes with the wheel R. To the outer end of the said shaft is attached a crank-wheel, U.

To the upper end of the frame A, between the upper ends of the inclined track-bars, B is journaled a pulley or drum, V.

W represents a rotating weighted drum, 60 which is provided with a central shaft, W', on the ends of which are fixed spur-pinions W², which mesh with the teeth of the rack-bars C. A depending frame, X, is hinged to the shaft W', and carries roller-wheels Y at its lower end, which bear against the outer 65 sides of the track-bars B. Near the upper ends of the frame X are journaled bearing-rollers Z, which bear against the rear sides of the track-bars B.

a represents a rope, one end of which is attached to the drum F. The said rope passes over the drum or pulley V, and has its outer end attached to the periphery of the weighted drum W.

b represents a cylinder, which is open at 75 one end and has its opposite extremity reduced, as at c, thereby forming a cone, which is provided with an opening, d. This cylinder is bolted or otherwise secured to the horizontal beam e, which is attached to the frame 80 A. A piston, f, works in the cylinder b, and is provided with the usual piston-rod, which is connected to the crank-wheel P on the shaft N by means of a pitman, g.

In the opening b works a valve, h, which is 85 attached to the upper end of a rocking arm, i. The said arm is fulcrumed to the outer end of the beam e, and to the lower end of the said arm is attached a rod, k, the free end of which is provided with a series of notches or serrations, l. The outer end of the said rod passes through a slot which is made in the plate m, that is secured to the frame A, and the said serrations or notches are adapted to engage the bottom of the slot.

95 n represents a pump-rod attached to the crank-wheel U on the shaft S.

The operation of my invention is as follows: By turning the shaft H in the reverse direction to that indicated by the arrows in Fig. 1, 100 the drum F is rotated independently of the shaft D, thereby coiling the rope a upon the

drum F and uncoiling it from the weighted drum W. As the rope is uncoiled from the drum W it will be readily understood that the latter will be rotated in the reverse direction 5 to that indicated by the arrows 1 in Fig. 1, thereby causing the said drum to be raised upon the track until it reaches the upper end thereof. When the crank of the shaft H is released, the weight of the drum W causes it 10 to descend, and as its spur-wheels mesh with the toothed bars of the inclined track the said weighted drum is rotated in the direction indicated by the arrows 1 in Fig. 1, thereby coiling the rope a upon the said weighted drum 15 and uncoiling it from the drum F. This causes the said drum F to rotate in the direction indicated by the arrows in Fig. 1, thus imparting motion to the train of gearing and actuating the shaft S, and thus reciprocating the 20 pump-rod. The piston f is also reciprocated in the cylinder b, and when the valve in the reduced end of said piston is open the air is alternately sucked into and ejected from the said cylinder. By partly closing the valve by 25 moving the serrated rod the passage of the air through the opening in the cylinder is obstructed and retarded, thereby increasing the resistance of the air through the piston f, and consequently adding increased load to the 30 train of mechanism, thus serving as a brake therefor. When the valve is moved so as to entirely close the opening in the cylinder, the air therein becomes so closely compressed by the piston f as to offer very greatly increased 35 resistance to the operation of the machine, and it will thus be readily understood that by moving the valve so as to regulate the opening d in the cylinder the brake may be caused to be applied to the motor at any desired pressure, 40 thus regulating the operation of the motor to any required speed.

I do not desire to limit myself to the precise construction hereinbefore shown and described, as it is evident that many modifications may be made therein without departing 45 from the spirit of my invention, the essential feature of which is the rotating descending weighted drum W, the operating-drum F for the motor, and the rope connecting the said 50 drums, whereby when the drum W descends the rope is coiled thereon and uncoiled from the drum F, causing the latter to rotate, and vice versa.

In Fig. 4 I show a modified form of my invention, in which the rack-bars and the spur-pinion of the weighted drum are dispensed with. The ends of the shaft of the weighted

drum form drums w, the heads of which at their outer ends bear against the inclined track-bars. Ropes z, which depend from the upper 60 side of the frame A, are coiled upon the drums w in the reverse direction to the rope a upon the drum W, thus adapting the said ropes z to perform the same function as the rack-bars C and the spur-pinion W', and cause the weight- 65 ed drum W to coil the rope a upon it when the said drum descends, and to uncoil the rope a when the drum ascends.

The modification shown in Fig. 5 differs in no essential particular from the construction 70 shown in Figs. 1, 2, and 3, except that two drums, 1 2, are employed instead of drum F of Fig. 1, and two ropes with their attachments added to accommodate the drums. The said drums are caused to rotate in unison by means 75 of an endless chain, which passes over sprocket-wheels at the ends of the drums.

Having thus described my invention, I claim—

1. The combination, in a motor, of the 80 rotating descending weighted drum W, the operating-drum F for the motor, and the rope connecting the said drums, whereby when the drum W descends the rope is coiled thereon and uncoiled from the drum F, which is caused 85 to rotate in one direction, and when the said drum F is rotated in the contrary direction the rope is coiled thereon and uncoiled from the drum W, thereby rotating and elevating the latter, substantially as described. 90

2. The combination, in a weight-motor, of the inclined track-bars having the spur-teeth C, the drum F for the motor, the weighted drum W, having the spur-pinion W', engaging with the rack-teeth C, the pulley or drum 95 V at the upper end of the inclined track, and the rope a, having one end attached to the drum F and the other end attached to the drum W, substantially as described.

3. The combination, in a weight-motor, of 100 the shaft D, having the ratchet L and the loose drum F, the descending rotating weighted drum W, the pulley or drum V, the rope connecting the drums F and W, and means for rotating the drum F independently of its shaft 105 D, for the purpose set forth, substantially as described.

In testimony that I claim the foregoing as my own I have hereto affixed my signature in presence of two witnesses.

THOMAS JEFFERSON BLAGG.
